UNITED STATES PATENT OFFICE.

ANDREJ ZABAWA, OF SHAWENEGAN FALLS, QUEBEC, CANADA.

FOLDING FURNITURE.

1,303,446.

Specification of Letters Patent.

Patented May 13, 1919.

Application filed July 2, 1918. Serial No. 243,047.

To all whom it may concern:

Be it known that I, ANDREJ ZABAWA, a citizen of Poland, residing at Shawenegan Falls, Province of Quebec, Canada, have invented certain new and useful Improvements in Folding Furniture, of which the following is a specification.

This invention relates to improvements in folding furniture, and particularly to tables and chairs, the main object of the invention being to provide a table or stand having combined therewith a plurality of seats conveniently arranged when in an extended position, or which may be so folded as to occupy no room other than that taken by the table, such furniture combination being extremely convenient for use upon lawns, parks and the like for picnics and other like purposes.

20 This and other like objects are attained by the novel construction and combination of parts hereinafter described and shown in the accompanying drawings, forming a material part of this disclosure, and in 25 which:—

Figure 1 is a side elevational view, showing a table and chairs made in accordance with the invention.

Fig. 2 is a horizontal, sectional view taken 30 on line 2—2 of Fig. 1.

Fig. 3 is a fragmentary side elevational view, showing the chairs as folded in connection with the table, and

Fig. 4 is a front elevational view, looking 35 from the back of a chair when in a folded position.

The invention comprises a rectangular platform or base 14, having central extensions 15, at each of its four sides, while 40 rigidly engaged upon the top of the platform 14, are columns 16, supporting a plate or table top 18, provided with braces 19 in the usual manner.

Plate-links 20 are engaged by hinges 21 with the extensions 15, and engaged by pins 45 23 at the outer corners of the links 20 are bars 24 connected at their other ends by pins 25 with the chair seats 26, the seats having cleats 27 extending across their front lower edge forming an abutment adapted to 50 receive the beveled ends 28 of bars 29 pivoted by the pins 30, to the bars 24, the opposite lower ends of the bars 29, being beveled so as to rest securely upon any substantially level foundation. Chair backs 32 55 are engaged to the seats 26 by hinges 33, while pivoted to the backs by the pins 34, are arms 35, having open slots 36, at their lower ends engageable with pins 38, set in the sides of the seats 26.

60 The construction of the table is that of an ordinary plain type, while the chairs are comprised of elements so jointed as to be compactly folded against the table, permitting easy transportation of the complete 65 structure, while the several parts may be extended or folded as will be evident.

Having thus described my invention what I claim as new and desire to secure by Letters Patent, is.

70 In combination, a table having a rectangular top and corner supports extending downwardly from said top, a plate upon which said supports are rigidly engaged, lateral extensions from each of the rectangular 75 edges of said plate, plate links having outwardly flaring side faces hinged to said lateral extensions, collapsible chair legs pivotally secured to the outer edges of said links, and chair seats and backs connected 80 to arm rests, all of these parts adapted to be folded upon said plate.

In testimony whereof I have affixed my signature.

ANDREJ ZABAWA.
